US0D1014510S

(12) **United States Design Patent** (10) **Patent No.:** **US D1,014,510 S**
(45) **Date of Patent:** **** Feb. 13, 2024**

(54) **JOYSTICK MOUNT**

(71) Applicant: **Chusong Chen**, Foshan (CN)

(72) Inventor: **Chusong Chen**, Foshan (CN)

(**) Term: **15 Years**

(21) Appl. No.: **29/915,220**

(22) Filed: **Oct. 27, 2023**

(51) **LOC (14) Cl.** **14-02**

(52) **U.S. Cl.**

USPC **D14/454**

(57) **CLAIM**

The ornamental design for a joystick mount, as shown and described.

DESCRIPTION

FIG. 1 is the first perspective view of our new design; FIG. 2 is the second perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; and, FIG. 9 is the third perspective view shown in an alternative position thereof. The broken lines in the drawings depict portions of the joystick mount and form no part of the claimed design.
